SHIP'S STERN

Vladimir Yourkevitch, Paris, France

Application August 2, 1935, Serial No. 34,331
In France December 6, 1934

2 Claims. (Cl. 114—56)

This invention relates to the hulls of ships and is directed to novel configurations in the stern or aft portion thereof and more especially below the waterline.

5 One object of the invention is to stiffen the aft portion of propeller driven ships in such manner as to minimize vibration resulting from the operation of the propellers and from other causes. This vibration, which is particularly noticeable at certain speeds, is very annoying and uncomfortable because of its persistency and this persistency of vibration becomes, with time, prejudicial to shell plating and structure of the ship.

15 My experiments and research in this connection have convinced me that this difficulty is largely due to the inherent properties of hull construction as heretofore designed and which result in hull forms having appreciable overhang 20 at the stern, making it impossible to properly brace said stern portion or incorporate therein the desirable inherent buoyancy or displacement. As a result, the stern portions of ships, in the great majority of cases, project in an aft direction beyond the buoyant body of the hulls and this constitutes an ideal condition for vertical and lateral whip, particularly in overhang portions of the hull.

With these considerations in mind, the present 30 invention provides for materially increased longitudinal and lateral stiffness and rigidity of the stern portion of the hull, so as to properly reinforce the same against lateral whip as well as vertical vibration.

35 Another object of the invention is to increase the speed of ships of the faster type, through the employment of novel stern construction. This object of the invention, has to do, more particularly, with naval destroyers, cruisers and the like, which travel at express speeds, although this feature will also be of advantage in fast ships, other than naval vessels. For example, when a destroyer is traveling at high speed, it has a pronounced tendency to "squat" at the 40 stern. In other words, the bow appreciably rises, while the stern correspondingly lowers in the water, thus causing a partial up-ending of the hull which, in case of an exaggerated squatting, increases its resistance to passage through the 45 water. The present invention, when adapted to hulls of this character, serves to so increase the buoyancy of the stern or aft portion of the hull as to minimize this settling effect at high speeds, in order that the hull may be maintained at 50 a more even keel. Resistance against longitudi-

nal movement of the hull is thus lessened and the speed materially increased without change in driving horsepower of the vessel.

Another object of the present invention, desirable in all hulls, but particularly in hulls of fast moving vessels, is to increase the efficiency of the propellers by properly directing the flow of water past the hull in such manner that it is fed to the propellers in the most efficient way. Various expedients have been resorted to in hull 10 construction to this end, but the majority of them which seek to direct the flow of water to the propellers counteract any increased efficiency thereof by the building up of increased resistances to forward movement of the hull. For example, 15 it has been proposed to fit all sort of fins guiding water towards propellers or to broaden the hull directly forward of the propellers in various ways, in order to cause the water to be drawn inwardly back of such enlargements and into 20 the grip of the propellers, but these expedients, although tried in various ways, have not proven satisfactory and they tend to slow down the boat due to increased resistance.

The present invention accomplishes efficient 25 propeller operation in a thoroughly satisfactory way and through the formation, within the contour of the hull below the waterline, of channels which extend fore and aft and are of convergent-divergent contour, so as to produce, in effect, a 30 substantially Venturi contour channel at each side of the hull, so that, as the hull of the ship moves forwardly, the water streams flow smoothly through these channels with a minimum width of hull cross section between them. These 35 streams unite back of the rudder, which is interposed between said streams, in long flowing lines, so as not to set up eddies or result in appreciable resistance.

The propellers are mounted to partially project within said channels and are preferably juxtaposed with contracted section of the above channels so as to cause the propeller tips to operate sensibly within the channels' gullets and so as to receive the water streams in a most efficient way. Contraction of the water flow by these Venturi-like channels produces sidewise an injector action on the adjacent water streams which are drawn in a wide flow towards the propellers, the efficiency of which is materially increased because of this accelerated flow of water.

An important feature of this invention resides in the formation of what may be termed a bulbous cross section at the keel, in the vicinity of the propellers, and extending forwardly and aft

therefrom and tapering off in both directions into a substantially torpedo shape. Such a bulbous formation at the keel produces several of the advantages to which I have hereinbefore referred. When made of the tapering form, simulating a torpedo shape, instead of materially increasing the resistance to forward movement of the hull as all other water-guiding protuberant devices, such as deflectors, fins, nozzles, etc., invariably occasion, this bulbous keel formation reduces on the contrary the resistance. At the same time it increases the buoyancy through increased displacement of the stern portion of the hull. It reduces the so-called squatting. It allows of proper reinforcement of the stern portion of the hull by providing backbone at the keel, so as to minimize vertical or lateral vibration or whip. It permits of the narrowing of the hull in the vicinity of the water line, in view of a further reduction of the resistance, the deficient displacement on the water line being counterbalanced by the additional displacement of the bulbous keel formation. It provides a convenient means for the formation of the convergent-divergent channels to which I have referred and it provides additional fuel or cargo space if this is desired. It also may be utilized to serve as a water ballast tank, through the regulation of the contents of which the hull may be properly "trimmed" in a fore and aft direction. Furthermore, when so used, the ballast is at the keel where it is most efficient in preventing rolling or wallowing in a heavy sea or cross swells.

Another important feature of the present invention, as will hereinafter be more fully described, resides in the reinforcing of the keel at the stern, as hereinbefore explained, so that the lower end of the stern post may be properly anchored and an enclosed rudder used, which rudder may be either of the balanced or unbalanced type.

Features of the invention, other than those adverted to, will be apparent from the hereinafter detailed description and claims, when read in conjunction with the accompanying drawing.

The accompanying drawing illustrates one practical embodiment of the invention, but the drawing is to be understood as illustrative, only, and not as defining the limits of the invention. Figure 1 is a side elevation of a stern of a conventional hull.

Figure 2 shows plan traces of the stern portion and waterline contour of the hull portion of Figure 1.

Figure 3 shows the so-called "body plan" or vertical traces of several transverse frames of the hull indicated in Figure 1.

Figure 4 is an outline cross section taken at the section line 4-4 of Figure 1 and showing deck lines, shell plating and waterline.

Figures 5 and 6 give a simplified image of the mechanical properties of the stern section of the hull of Figure 1.

Figures 7, 8, 9 and 10 correspond to Figures 1, 2, 3 and 4 of the drawings of a conventional hull, but show a hull embodying the present invention.

Figure 11 corresponds to Figure 5 but gives a simplified image of the mechanical properties of the hull of the present invention.

Figure 12 is a comparative graph of the areas of cross sections of the hull and of the weights or loadings of different hull constructions.

It is felt that the present invention may be best understood if explained in connection with

present day conventional construction, and I have accordingly illustrated, in the accompanying drawing, conventional hull construction and by comparison have shown the hull of the present invention. It should be understood in this connection that the two hulls here compared relate to boats of the same class or kind and that the present invention may be modified in adapting the same to hulls of various types.

Referring first to Figures 1-6, these figures represent a conventional hull of a fast vessel indicated by the reference character 10, and the contours of which hull are not only narrowed in the vicinity of the load waterline 11, in view of reduction of the resistance, as will be apparent from the successive equidistant transverse sections or frames indicated at 1, 2, 3, 4 and 5 in Figures 1-3, but also are tapered upward aft in vertical plan for the same purpose.

When a hull is thus narrowed and formed as shown, it will have an appreciable overhang at the stern and in practice, it may be likened structurally to a spring 12, as shown in Figure 6. This spring has superimposed leaves 13, 14, 15, etc. rendering the same vertically resilient as it extends from its zone of anchorage 16. The overhanging stern of the hull of Figures 1 and 2 possesses the same broad peculiarities because the ship construction is unavoidably of a more or less resilient nature and possesses some "give" when made as described, as the overhang stern portion must be of a light construction and does not allow of sufficient internal bracing to make it rigid. As a result, the stern of the ship of Figure 1 will vibrate vertically under the action of the propellers indicated at 17 and under buffeting of the seas. Similarly, since the stern is relatively narrow, particularly below the waterline 11, this portion of the hull will have an inherent tendency to weave or whip laterally due to the operation of the propellers and to the passage of water streams past the rudder.

Graphically, the cross section of the hull, at the section line 4-4 of Figure 3, may be compared, for practical purposes, to a girder section, such as shown in Figure 5, in which the upright web 18 corresponds to the vertical dimension of the hull, while the flanges 19 and 20 correspond to the decks or other internal bracing. This section is taken in the vicinity of the propellers but aft of this the vertical dimension of the hull decreases rapidly until it is relatively shallow. Thus a girder of the kind shown will be susceptible to appreciable vertical deflection as well as appreciable lateral deflection, particularly in the lower portion of the web 18 thereof, under the action of the propeller and the other forces to which I have referred and this deflection will of course increase progressively aft. This is one reason for pronounced vibration in the stern of ships as now constructed and, prior to this invention, no adequate solution has been found to minimize the same to a point where it will not be uncomfortable to the passengers or where it will not produce undesirable strains on the hull structure. The present invention solves this problem in a simple and efficient manner.

Thus, as shown in Figures 7-11, the rear frames, at the successive transverse sections 1, 2, 3, 4 and 5 are formed with appreciable hollows 70 accentuated in the region of the load waterline 11 and end in the region of the keel in pronounced bulbous contours formed by club-footed frames and indicated generally at 21. The traces shown result in a bulbous keel portion in-

dicated generally by the reference character 22, which tapers fore and aft from its greatest vertical and horizontal dimensions, so that it may be said to be substantially torpedo shape in a longitudinal direction of the hull. This so-called 5 bulbous portion may vary in cross section without departing from this invention, but I preferably make the same substantially in the shape of a waterdrop, as shown in Figure 10, whereby 10 the superimposed portion of the hull is joined to the bulbous keel portion 22 by a relatively thin intervening submerged section 24 producing a substantially hour glass section to form, at either side thereof, channels 24 which extend longitudinally 15 of the hull. By virtue of the formation of the superimposed structure and the underlying bulbous portion, these channels converge rearwardly from their forward open ends to a point of minimum dimension, indicated generally by 20 the region 23 in longitudinal view, and aft of this region the channels flare out rapidly so as to produce, in each, a divergent-convergent longitudinal contour, somewhat similar to a longitudinally sectioned Venturi tube of which the 25 outer half is removed. The propellers, shown as twin propellers, and indicated at 17, are positioned in the region of minimum dimension of these channels and are so mounted, as illustrated in Figures 7 and 10, as to project into and operate 30 within the channels.

It will thus be noted that the hollowing out and club-footing of the frames as stated produces the two convergent-divergent semichannels 35 leading to and from the propellers and these function after the manner of nozzles for the induction of water to the propellers and the discharge of water therefrom. In practice, the said channels smooth out the water streams and lead them to the propeller from a point below, so as to permit the propellers to operate with 40 the greatest efficiency and at the same time minimize the drag of surface water into the propellers with resulting absorption of air bubbles and fall of efficiency of propellers. In fact, it is found that the propellers tend to suck the 45 water longitudinally of the channels and produce a pronounced suction therein which materially decreases resistance to the forward passage of the hull, while the water leaving the propellers is discharged through a rapidly diverging space 50 directly to the rudder. This directed water flow produces an increased reaction on the stern of the hull and contributes to forward progression of the ship. Thus, instead of increasing the 55 resistance to the movement of the ship, as has heretofore been the case with all known means of directing water to the propellers, the structure of the present invention decreases this resistance considerably, so that I am able to fully utilize the increased efficiency of the propellers for the 60 forward movement of the hull.

By positioning the propellers above the bulbous portion, so as to project into the channels, I further produce a condition particularly propitious for the support of the outboard ends of the propeller shafts. Heretofore the outboard ends of these tall shafts have been carried by propeller struts forming parts of brackets which are riveted exteriorly to the hull in depending position 65 and generally each comprises two V shaped arms arranged in angular relation to one another at a relatively acute angle, as shown in Figure 4 at 28'. This arrangement does not produce a rigid mounting. By reference to Figure 10, however, it will be noted that the arms of the struts 70

28 of the present invention are positioned in substantially right angular relation to one another and at the same time substantially normal to the surfaces of the portions of the hull to which they are fixed, so as to more effectually 5 support the shaft bearings. This arrangement is made possible by the rugged bulbous portion which is sufficiently strong to withstand the lateral thrust and constitutes in effect the backbone of the ship at this point. 10

The bulbous keel portion 22 preferably extends substantially to the stern post 25 which, instead of being composed of assembled pieces of cast iron of complex design and shape as heretofore, may be conveniently formed, according to the 15 present invention as shown in Figure 7, with the stern post carried around and anchored to the aft end of the bulbous portion which constitutes a firm anchorage therefor. The rudder 26 may be mounted, as shown, within the confines of the 20 stern post and properly contoured in the usual way.

Another advantage of this stern post arrangement is that it ties together the aft end of the bulbous portion and the extreme stern of the 25 hull and assists in producing an efficacious reinforcement of the entire stern of the hull. It will of course be understood that the stern post may be shaped otherwise than as shown in Figure 7, but it preferably is carried well down to the keel 30 and anchored to the bulbous portion 22 as stated.

When the hull is formed, as shown in Figures 7-10, it will be noted that a mechanical result 35 illustrated in the girder form of Figure 11, is produced as compared to the structure shown in Figure 5. In Figure 11, the web 18' of the girder is deeper and in addition to the decks 19 and 20, the web of the girder is provided at its lower edge with additional lateral flanges 27, which are of appreciable width and indicate the 40 structural strength or reinforcement factor of the bulbous part 22. This additional flange 27 manifestly not only increases the strength and rigidity of the increased web height, but it also very materially increases these factors in a lateral direction. In other words, it gives the ship 45 backbone in its aft end at the keel and precludes lateral whip of this part of the ship and at the same time reinforces the same against vertical vibration. This vibration is due to a great extent upon the operation of the propellers as 50 stated, but when the streams of water fed to and from the propellers are controlled as described, this also minimizes vibration.

It should be further noted that the bulbous 55 portion 22 results in additional displacement well below the waterline and consequently increased buoyancy at this point which, as shown in Figures 7 and 8, is directly forward of the stern post or as far aft as possible. This I have found to 60 be of pronounced advantage. For example, in conventional ship design for fast ships, there has invariably been a narrowing of the after portion with the object of decreasing the resistance to forward motion. This naturally decreases the 65 buoyancy of this aft extremity, so that there is a tendency of the ship to squat or lower in the water; particularly when the ship is traveling at high speeds. With the additional buoyancy however afforded by the bulbous portion 22, this does not occur and the ship is, in contradistinction, maintained on a more even keel. This holds good not only for a vessel traveling in smooth water, but also cutting through the seas in which case 70

the torpedo shaped bulbous formation acts as a kind of anti-pitching device.

The showing of Figure 12 graphically illustrates these distinctions by comparison. In this figure,

- 5 A represents the graph of the areas of the cross sections of the stern; this graph also represents, on a suitable scale, the graph of the displacements or the buoyancies of the corresponding parts of the ship. The broken line P represents
- 10 the repartition of the weights along the ship, the total areas delimited by graphs A and P being equal for the entire ship, because the displacement of a floating body is equal to its weight. Finally C is the graph of the loads which result from the
- 15 differences of the ordinates of the graphs A and P, the areas delimited by graph C representing in each transversal part the local excesses of the weight over the displacement, when they are located below the horizontal axis OY, and the local excesses of the displacement over the weight, when they are located above this axis. It can be seen that at the extreme rear end of the ship the weights overcome the buoyancy (hatched area L, Figure 12), and, as these weights are located at a great distance from the middle of the ship and therefore act on a long arm of the lever, they produce considerable pitching moments. The bulbous protuberance in the shape of a torpedo, formed, in accordance with the invention
- 20 by the club-footing of the stern frames, compensates for this excess of weight by increasing the displacement and thus decreases the pitching moments by the buoyancy of the stern. The graph of the areas of the cross sections A, instead
- 25 of joining itself tangentially to axis OY, produces an enlargement M, as represented by the dot and dash line in Figure 12; the hatched area K, located in this region between branch M and the old graph A, must be equal or superior to the
- 30 hatched area L, representing the excesses of the weights. Moreover, by utilizing the enlargement or bulbous part 22 of the bow and the stern as a water ballast chamber, it is possible to regulate, at will, the weight of the stern part and thus the
- 35 trim of the ship.

The present invention is preferably built into ships during the initial construction thereof, but

it may be also incorporated in old ships by removing the stern section of the hull and building on a new section embodying the invention. This new section may be so designed as to increase the length of the hull sufficiently to incorporate 5 thereto the present invention, although, if desired, more extensive portions of the aft section of the hull may be remodeled, although this is generally not desirable as it will materially increase the cost over and above that of the lengthening operation, which does not require appreciable modification of the remaining frames of the hull. The foregoing detailed description sets forth the invention in its preferred practical form, but the invention is to be understood as 15 fully commensurate with the appended claims. "Tapering" and "tapered", as used in the appended claims, means a gradual diminution of thickness.

Having thus fully described the invention, what 20 I claim as new and desire to secure by Letters Patent is:

1. A ship's hull provided aft of amidships and forwardly of the stern post with a bulbous keel portion, a superimposed buoyant portion, and an 25 interposed upright portion of materially reduced cross section having concave sides which merge into the corresponding sides of the superimposed portion in substantially tangential relation thereto, said bulbous keel portion tapering both fore 30 and aft from a point intermediate its ends to form, at both sides of said interposed portion, convergent-divergent channels extending in a fore and aft direction, propellers partially projecting into said channels and juxtaposed substantially with the region of minimum cross section of said upright portion, and a stern post, the lower end of which is anchored to the aft end of said bulbous keel portion in substantially tangential relation thereto.

2. A ship's hull provided aft of amidships with a bulbous keel portion tapering in fore and aft directions, and a stern post anchored to the after end of the bulbous keel portion and extending rearwardly and upwardly in substantially tangential relation to the keel.

VLADIMIR YOURKEVITCH.
